ABSTRACT OF THE DISCLOSURE

A piezoelectric ceramic composition of the formula $(\text{Pb}_u\text{A}_v)(\text{Zr}_x\text{Ti}_y\text{Sn}_z)\text{O}_3$, where A represents at least one member selected from a group consisting of calcium, strontium and barium and u, v, x, y and z are given by

$$u=0.75-1.00 \quad v=0.00-0.25, \quad u+v=1.00 \\ x=0.00-0.90, \quad y=0.10-0.60, \quad z=0.00-0.65$$

and $x+y+z=1.00$, characterized in that said ceramic composition contains a set of additional constituents consisting of a chromium compound equivalent in amount to a chromium sesquioxide of from 0.01 to 0.30 weight percent and a cobalt compound equivalent in amount to a cobalt sesquioxide of from 0.02 to 0.50 weight percent, each of the weight percentages being the percentage of the total weight of said ceramic composition.

This is a division of application Ser. No. 587,242 filed Oct. 17, 1966, now U.S. Pat. No. 3,481,875.

This invention relates generally to piezoelectric ceramic compositions. More particularly, the invention relates to ceramic compositions based on a formula of lead zirconate-lead titanate $\text{PbZrO}_3=\text{PbTiO}_3$ or on a formula lead zirconate-lead titanate-lead stannate

The present invention relates more particularly to lead zirconate-lead titanate-lead stannate

ceramic compositions which contain, in addition to such compositions, chromium sesquioxide (Cr_2O_3) of from 0.01 weight percent to 0.3 weight percent of the total weight and also cobalt sesquioxide (Co_2O_3) of from 0.02 weight percent to 0.5 weight percent.

More particularly, the present invention also relates to $\text{PbZrO}_3=\text{PbTiO}_3=\text{PbSnO}_3$ ceramic compositions which contain, in addition to such compositions, manganous oxide (MnO) of from 0.02 weight percent to 0.5 weight percent of the total weight and also cobalt sesquioxide (Co_2O_3) of from 0.02 weight percent to 0.5 weight percent.

A general object of this invention is to provide ceramic compositions having large electromechanical coupling factors and large mechanical quality factors.

A further object of this invention is to provide piezoelectric materials which have both large electromechani-

2

cal coupling factors and large mechanical quality factors for use as elements of ceramic electric wave filters and as transducer elements of mechanical filters.

It can be established that a lead zirconate-lead titanate solid solution $\text{Pb}(\text{ZrTi})\text{O}_3$ obtained by sintering a mixture of lead zirconate PbZrO_3 and lead titanate PbTiO_3 , has piezoelectric properties which are stable against change of temperature and elapse of time and that strong piezoelectric activities are achieved in the neighborhood of $x=0.52-0.54$ in $\text{Pb}(\text{Zr}_x\text{Ti}_{1-x})\text{O}_3$.

Fundamental measures for evaluating the piezoelectric properties of a piezoelectric material are its electromechanical coupling factor and its mechanical quality factor. The electrochemical coupling factor represents the efficiency of transforming electric oscillation into mechanical vibration and, conversely, of transforming mechanical vibration into electric oscillation. The mechanical quality factor represents the reciprocal proportion of the energy consumed by the material during the electrical and mechanical energy interconversion. A larger mechanical quality factor corresponds to a smaller energy consumption by the material, and vice versa.

Recently, attention and studies have been directed to ceramic electric wave filters wherein use is made of piezoelectric ceramics as the element or elements of the filters, and to mechanical filters wherein use is also made of piezoelectric ceramics as the transducer or transducers thereof. The qualities desired for the piezoelectric ceramics used in these fields of applications are as follows:

For the elements of ceramic electric wave filters, the electromechanical coupling factor must have a desired value selected from a range between an extremely large value and a very small value, and the mechanical quality factor should have as great a value as possible. For the transducer elements of mechanical filters, both the electromechanical coupling factor and the mechanical quality factor must be as large as possible. Thus, the properties required for the transducer elements of mechanical filters are consistent with that particular set of properties demanded for the elements of ceramic electric wave filters in which the electromechanical coupling factor is large.

The electrochemical coupling factor determines the frequency spacing between the attenuation poles of the filter in such a manner that a greater electromechanical coupling factor produces a filter of wider frequency spacing and a smaller electromechanical coupling factor results in a filter of narrower frequency spacing. In other words, the electromechanical coupling factor of the piezoelectric material for the elements of ceramic filter must be selected in compliance with the frequency spacing between the attenuation poles of the particular filter in which the material is to be used and that factor must therefore be available or adjustable between an extremely small value and a very large value according to the characteristics of the filter. The mechanical quality factor also determines the loss in the pass band and the loss at the attenuation poles of the filter. The values desired for a filter therefore determine the lowest allowable limit of the mechanical quality factor of the piezoelectric material to be used in the filter. In other words, a piezoelectric material having a smaller mechanical quality factor than required can not provide a satisfactory filter,

while a piezoelectric material having a greater mechanical quality factor than required can easily provide a filter of excellent characteristics. A greater mechanical quality factor is generally necessary for piezoelectric materials to be used in a filter of narrower pass band or for a case where a smaller electromechanical coupling factor is required.

As has so far been described, piezoelectric material for use in filters must be furnished with the electromechanical coupling factor selected from a wide range according to the characteristics and the fields of application of the particular filter and with the largest possible mechanical quality factor.

According to this invention, the basic composition of lead zirconate-lead titanate $Pb(Zr_{0.52}Ti_{0.48})O_3$ may incorporate either one of two pairs of additives above-noted, that is, Cr_2O_3 and Co_2O_3 , or MnO and Co_2O_3 , in the required amounts, and in such basic composition at least one member of the group of barium (Ba), strontium (Sr) and calcium (Ca) may replace up to 25 atom percent of the lead (Pb) contained in the basic composition.

Details of certain earlier types of replacements or substitutions in piezoelectric materials are generally described, for example, in "Journal of the National Bureau of Standards," 55 (1955), 239 by B. Jaffe, R. S. Roth, and S. Marzullo and in U.S. Pats. No. 2,906,710 issued to F. Kulcsar et al. on Sept. 29, 1959, and No. 3,068,177 issued to J. A. Sugden on Dec. 11, 1962.

This invention may also be expressed as residing in a piezoelectric ceramic composition whose basic composition may be a lead zirconate-lead titanate-lead stannate $PbZrO_3$ - $PbTiO_3$ - $PbSnO_3$ solid solution as already noted. This basic composition may be expressed by the term

where the ranges for x , y , and z are mol ratios given by
 $x=0.00-0.90$,
 $y=0.10-0.60$,
 $z=0.00-0.65$, and
 $x+y+z=1.00$,

in order that the piezoelectric material may have an electromechanical coupling factor of a satisfactory value. Compositions outside of the suggested ranges are not practically operable because of their seriously reduced electromechanical coupling factors. The largest electromechanical coupling factor is obtainable in cases in which x , y , and z are in the vicinities of 0.52-0.53, 0.48-0.47, and 0.00, respectively. Also, excellent piezoelectric properties are obtained even if at least one member of the group of calcium, strontium and barium may be substituted for up to 25 atom percent of the lead contained in the basic composition.

It is especially noted, as will be explained by way of example, that improvements in the characteristics of the various compositions may be brought about by the addition of cobalt sesquioxide, chromium sesquioxide and manganese oxide in the amounts and in the combinations specified hereinafter, and such improvements clearly result from the presence of cobalt ions, chromium ions and manganese or manganese ions, respectively, in the lead zirconate-lead titanate ceramics. Similar cobalt compounds (for example, $CoCO_3$), other than cobalt sesquioxide (Co_2O_3), may also be used in the composition so as to provide an amount of cobalt ions equal to the amount of cobalt ions provided by cobalt sesquioxide (Co_2O_3) when it is used in the composition. Also, similar chromium compounds (for example, $CrCl_3$), other than chromium sesquioxide (Cr_2O_3), may be used in the composition so as to provide an amount of chromium ions equal to the amount of chromium ions provided by chromium sesquioxide (Cr_2O_3) when it is used in the composition. Furthermore, if manganese or manganese compounds, other than MnO , are utilized, they should be used in amounts equivalent to the desired weight of MnO .

Particularizing further, the compositions of this invention may also consist of another basic composition of $Pb(Zr_xTi_ySn_z)O_3$ where x , y , and z are given by the above equations and where at least one member of the group of calcium, strontium and barium may be replaced by up to 25 atom percent of lead (Pb) contained in the basic composition, and such basic composition may include additional constituents of cobalt sesquioxide (Co_2O_3) of from 0.02 weight percent to 0.5 weight percent and also manganese oxide (MnO) of from 0.02 weight percent to 0.5 weight percent.

The resulting basic compositions above-noted are especially suitable as piezoelectric materials for the elements of electric wave filters and for the transducer elements of mechanical filters.

As for the piezoelectric materials to be used in the elements of ceramic electric wave filters, it is necessary that such materials provide an electromechanical coupling factor with an optimum value selected from a wide range extending from an extremely large value to a very small value, and it is also desirable for the mechanical quality factor to have as great a value as possible. This criterion is described, for example, in "Electronic Engineering," vol. 33 (1961), No. 3, pp. 171-177, by R. C. V. Macario, entitled, "Design Data for Band-Pass Ladder Filters Employing Ceramic Resonators."

This invention will be better understood from the more detailed description hereinafter following when read in connection with the accompanying drawing in which:

30 FIG. 1 shows curves representing the electromechanical coupling factor Kr for the radial mode vibration and the mechanical quality factor Qm , both plotted as ordinates, against abscissae representing the content of cobalt sesquioxide (Co_2O_3) in ceramics obtained by adding, to the composition $Pb(Zr_{0.52}Ti_{0.48})O_3$, the compound chromium sesquioxide (Cr_2O_3) of 0.1 weight percent and the compound cobalt sesquioxide (Co_2O_3) of up to 0.5 weight percent. This composition is exemplified in Table 1 hereinafter.

40 FIG. 2 shows curves representing the factors Kr and Qm , both plotted as ordinates, against abscissae representing the content of chromium sesquioxide (Cr_2O_3) in ceramics obtained by adding, to the composition

45 the compound cobalt sesquioxide (Co_2O_3) of 0.10 weight percent and the compound chromium sesquioxide (Cr_2O_3) of up to 0.3 weight percent. This composition is exemplified in Table 2 hereinafter.

50 FIGS. 3 and 4 show similar curves representing the electromechanical coupling factor Kr for the radial mode vibration and the mechanical quality factor Qm . The abscissae of FIG. 3 are related to the compound Co_2O_3 while the abscissae of FIG. 4 are related to the compound MnO . The curves of FIG. 3 are based on the compositions given in Table 6 while the curves of FIG. 4 are based on the compositions given in Table 7.

EXAMPLE 1

Results shown in Table 1

60 So that the resulting basic composition may be represented by $Pb(Zr_{0.52}Ti_{0.48})O_3$, namely, by $x=0.52$ and $y=0.48$, a powder consisting of 50 mol percent of lead monoxide (PbO), 26 mol percent of zirconium dioxide (ZrO_2), and 24 mol percent of titanium dioxide (TiO_2), a compound of 0.10 weight percent of chromium sesquioxide (Cr_2O_3) as an additional constituent, and another compound of cobalt sesquioxide (Co_2O_3) as a further additional constituent, arranged in various proportions between 0.02 weight percent and 0.50 weight percent as indicated in Table 1, are mixed, respectively, in a ball mill. Mixed powder of the respective kinds is presintered at 900° C. for an hour, crushed, press-moulded into discs, and sintered at 1300° C. for an hour. The resulting ceramic discs are provided with silver electrodes and piezo-

electrically activated through polarization treatment at 100° C. for an hour under an electric field of 50 kv./cm. After the discs have been allowed to stand for 24 hours, the electromechanical coupling factor Kr for the radial mode and the mechanical quality factor Qm are measured to evaluate the piezoelectric activities. Typical results are shown in Table 1.

¹ Cr₂(SO₄)₃ was added as calculated on the basis of Cr₂O₃.

material having substantially raised Kr and Qm factors. Further increases in the Kr and Qm factors, which have already been increased by the addition of Cr₂O₃ provide still greater improvements in the piezoelectric materials which would have wider fields of application. Comparison of the results Nos. 1 and 2 with the results Nos. 3 through 8 proves that addition of both Cr₂O₃ and from 0.02 weight percent to 0.50 weight percent of Co₂O₃ greatly increases the Kr and Qm factors. In general, an increase in one of the Kr and Qm factors results in a decrease in the other factor. However, the addition of both Cr₂O₃ and Co₂O₃ to the basic composition improves both the Kr and Qm factors and makes it possible to realize piezoelectric materials having Kr and Qm factors both of which are increased in magnitude. This material is excellent for use as the piezoelectric material in ceramic electric wave filters where a large Kr factor is required and in transducers of mechanical filters.

Referring to FIG. 1, the above-mentioned relation between the content of Co₂O₃ and the piezoelectric properties Kr and Qm are plotted for results Nos. 2 through 8 of Table 1. The curves quite clearly show that excellent piezoelectric materials are produced when the content of Co₂O₃ falls between 0.02 weight percent and 0.50 weight percent.

If the content of Co₂O₃ is less than 0.02 weight percent, the combination or coexistence of Cr₂O₃ and Co₂O₃ hardly improves the piezoelectric activities achieved by the presence of Cr₂O₃ alone. If the content of Co₂O₃ exceeds 0.50 weight percent, no substantial improvement is obtained in the factors Kr and Qm which would otherwise be attained through the coexistence of Cr₂O₃ and Co₂O₃. More particularly, if Cr₂O₃ is added when the proportion of Co₂O₃ is greater than 0.50 weight percent, the presence of Co₂O₃ alters the piezoelectric properties as already noted and the addition of Cr₂O₃ hardly contributes to the improvement of the properties.

In view of the above, a range between 0.02 weight percent and 0.50 weight percent is selected for the effective content of Co₂O₃.

Comparison of the result No. 9 with the result No. 1 of Example 1 shows that addition of 0.10 weight percent of Co₂O₃ alone to the basic composition provides a piezoelectric material having considerably elevated Kr and Qm factors. It should be understood, however, that further increases in the Kr and Qm factors, otherwise raised by addition of Co₂O₃, would provide piezoelectric materials of considerable improvement and having wider fields of application. Such further increases are achieved as shown in Table 2, by addition of both Cr₂O₃ and Co₂O₃.

Referring to FIG. 2, the piezoelectric properties Kr and Qm are plotted versus the content of Cr₂O₃ with respect to the results cited in Table 2 and to the result No. 5 of Table 1. The curves quite clearly show that excellent piezoelectric materials are obtainable when the content of Cr₂O₃ falls between 0.01 weight percent and 0.30 weight percent.

Even with coexistence of Cr₂O₃ as additives to the basic composition above-noted, less than 0.01 weight percent of Cr₂O₃ hardly improves the piezoelectric properties otherwise attained by the addition of Co₂O₃ alone. Also, when more than 0.30 weight percent Cr₂O₃ is added, improvement in the properties by coexistence of Cr₂O₃ and Co₂O₃ is hardly expected.

In view of the above, the effective content of Cr₂O₃ has been found to fall within a range between 0.01 weight percent and 0.30 weight percent for obtaining improved piezoelectric properties.

As already suggested above, the improvements made in the piezoelectric properties by the addition of Cr₂O₃ and Co₂O₃ clearly result from presence of chromium and cobalt ions. Chromium and cobalt ions may be introduced into the combination in various ways. Either chromium and cobalt oxides by themselves, or compounds thereof, which are easily decomposed at higher temperatures into the respective oxides such as shown in Tables 1 and 2, may be added to the powder of the raw materials of the basic composition during mixture thereof. For obtaining chromium ions, chromium sulfate [Cr₂(SO₄)₃] or the like

may be substituted for chromium sesquioxide (Cr_2O_3). For obtaining cobalt ions, cobalt carbonate (CoCO_3) or the like may be used instead of cobalt sesquioxide (Co_2O_3). These chromium and cobalt compounds, other than Cr_2O_3 and Co_2O_3 , should be used in their respective amounts which are equivalent to the desired amounts of Cr_2O_3 and Co_2O_3 , as exemplified by the results Nos. 4 and 7 in Table 1 and the result No. 13 in Table 2. In this connection, it should be understood that chromium sesquioxide (Cr_2O_3) or cobalt sesquioxide (Co_2O_3), as these terms appear hereinafter, may also mean the respective chromium or cobalt compounds which is easily decomposed at higher temperatures into chromium sesquioxide (Cr_2O_3) or cobalt sesquioxide (Co_2O_3).

EXAMPLE 3

Results shown in Table 3

Piezoelectric characteristics are shown in Table 3 for typical ceramics obtained by selecting values of 0.50-

5

15

where $x=0.47$, $y=0.48$, and $z=0.05$ and where $x=0.42$, $y=0.48$, and $z=0.10$ and those obtained by adding thereto 0.10 weight percent of Cr_2O_3 and 0.10 weight percent of Co_2O_3 .

Comparison of the result No. 5 of Table 1 with the results of Table 4 clearly shows that the substitution of tin for a portion of the basic composition does not harm the piezoelectric properties otherwise improved by the coexistence of Cr_2O_3 and Co_2O_3 . In other words, the piezoelectric properties of the ceramic materials having tin substituted for a part of the basic compositions are improved by the coexistence of Cr_2O_3 and Co_2O_3 as much as the ceramic materials having no tin substitution.

EXAMPLE 5

Results shown in Table 5

Table 5 shows the results obtained by substituting barium, strontium, and/or calcium for 5 atom percent of the lead in the composition No. 24 given in Table 4.

TABLE 5

No.	Composition	Kr, percent	Qm
25	($\text{Pb}_{0.95}\text{Ba}_{0.05}$) $(\text{Zr}_{0.42}\text{Ti}_{0.48}\text{Sn}_{0.10})\text{O}_3$ plus 0.10 wt. percent Cr_2O_3 plus 0.10 wt. percent Co_2O_3	58	1,280
26	($\text{Pb}_{0.95}\text{Sr}_{0.05}$) $(\text{Zr}_{0.42}\text{Ti}_{0.48}\text{Sn}_{0.10})\text{O}_3$ plus 0.10 wt. percent Cr_2O_3 plus 0.10 wt. percent Co_2O_3	60	1,250
27	($\text{Pb}_{0.95}\text{Ca}_{0.05}$) $(\text{Zr}_{0.42}\text{Ti}_{0.48}\text{Sn}_{0.10})\text{O}_3$ plus 0.10 wt. percent Cr_2O_3 plus 0.10 wt. percent Co_2O_3	56	1,260

0.55 and 0.50–0.45 for x and y , respectively, in the formula $\text{Pb}(\text{Zr}_x\text{Ti}_y)\text{O}_3$ and for those derived by adding thereto 0.10 weight percent of Cr_2O_3 and 0.10 weight percent of Co_2O_3 .

As is seen from Table 5, the piezoelectric properties are equally well improved by the coexistence of Cr_2O_3 and Co_2O_3 for both compositions in which there has been a substitution of at least one alkaline earth metal selected

TABLE 3

No.	Composition	Kr, percent	Qm
15	$\text{Pb}(\text{Zr}_{0.50}\text{Ti}_{0.50})\text{O}_3$	29	340
16	$\text{Pb}(\text{Zr}_{0.50}\text{Ti}_{0.50})\text{O}_3$ plus 0.10 wt. percent Cr_2O_3 plus 0.10 wt. percent Co_2O_3	55	1,330
17	$\text{Pb}(\text{Zr}_{0.47}\text{Ti}_{0.47})\text{O}_3$	41	300
18	$\text{Pb}(\text{Zr}_{0.47}\text{Ti}_{0.47})\text{O}_3$ plus 0.10 wt. percent Cr_2O_3 plus 0.10 wt. percent Co_2O_3	60	1,270
19	$\text{Pb}(\text{Zr}_{0.55}\text{Ti}_{0.45})\text{O}_3$	39	320
20	$\text{Pb}(\text{Zr}_{0.55}\text{Ti}_{0.45})\text{O}_3$ plus 0.10 wt. percent Cr_2O_3 plus 0.10 wt. percent Co_2O_3	56	1,320

Table 3 clearly shows that changes of x and y in the ceramic materials as noted, whose basic compositions are given by the above formulae, do not materially affect the piezoelectric properties otherwise improved by the coexistence of Cr_2O_3 and Co_2O_3 .

As a matter of fact, the compositions, improved by the addition of both Cr_2O_3 and Co_2O_3 , have excellent properties for use in manufacturing the elements of ceramic electric wave filters and the transducers of mechanical filters.

EXAMPLE 4

Results shown in Table 4

Table 4 shows the piezoelectric properties of Kr and Qm for ceramics given by the formula $\text{Pb}(\text{Zr}_x\text{Ti}_y\text{Sn}_z)\text{O}_3$,

from the group of any of the elements barium, strontium, and calcium for a portion of the basic composition and for compositions having no such substitution.

Examples 4 and 5 show that it is possible to provide an excellent piezoelectric material by addition of both Cr_2O_3 and Co_2O_3 , with the basic compositions consisting not only of lead titanate-lead zirconate solid solution but also of lead titanate-lead zirconate-lead stannate solid solution and, still further, with compositions in which a portion of the lead in these solid solutions is replaced by at least one alkaline earth metal.

As already observed, the piezoelectric ceramic composition improved as above noted can not be obtained by the addition of either Cr_2O_3 or Co_2O_3 alone, but only by the addition of both Cr_2O_3 and Co_2O_3 . It is further noted that the piezoelectric properties referred to are achieved through a polarization treatment performed at temperatures (about 50° C.–150° C.) higher than room

TABLE 4

No.	Composition	Kr, percent	Qm

22	$\text{Pb}(\text{Zr}_{0.47}\text{Ti}_{0.48}\text{Sn}_{0.05})\text{O}_3$ plus 0.10 wt. percent Cr_2O_3 plus 0.10 wt. percent Co_2O_3	58	1,260
23	$\text{Pb}(\text{Zr}_{0.42}\text{Ti}_{0.48}\text{Sn}_{0.10})\text{O}_3$	41	300
24	$\text{Pb}(\text{Zr}_{0.42}\text{Ti}_{0.48}\text{Sn}_{0.10})\text{O}_3$ plus 0.10 wt. percent Cr_2O_3 plus 0.10 wt. percent Co_2O_3	57	1,320

temperature. The polarization treatment, if carried out at room temperature, reduces the value of Kr. Consequently, polarization at room temperature is consistent with the object of this invention.

EXAMPLE 6

Results shown in Table 6

In order that the resulting basic composition may be represented by the formula $Pb(Zr_{0.52}Ti_{0.48})O_3$, such composition was set up from a powder consisting of 50 mol percent of lead monoxide (PbO), 26 mol percent of zirconium dioxide (ZrO_2), and 24 mol percent of titanium dioxide (TiO_2), to which was supplied a compound of 0.02 weight percent of manganous oxide (MnO) as an additional constituent, and then a compound of cobalt sesquioxide (Co_2O_3) of from 0.02 weight percent to 0.50 weight percent, as exemplified in Table 6, was added. These were mixed, respectively, in a ball mill. The mixed powder of the respective kinds was presintered at 900° C. for an hour, crushed, press-moulded into discs, and sintered at 1300° C. for an hour. The resulting ceramic discs were provided with silver electrodes and piezoelectrically activated at 100° C. for an hour under an electric field of 50 kv./cm. After the discs had been allowed to stand for 24 hours, the electromechanical coupling factor Kr for the radial mode vibration and the mechanical quality factor Qm were measured to evaluate

Referring to FIG. 3 of the drawing, the above-mentioned relation between the content of Co_2O_3 and the piezoelectric properties Kr and Qm are plotted for the results Nos. 2 through 8 of Table 6. The curves quite clearly demonstrate that excellent piezoelectric materials are produced when the content of Co_2O_3 falls between 0.02 weight percent and 0.50 weight percent.

When the content of Co_2O_3 is less than 0.02 weight percent, the coexistence of MnO and Co_2O_3 hardly improves the piezoelectric activities achieved by the presence of MnO alone. When the content of Co_2O_3 exceeds 0.50 weight percent, there would be substantially no improvement in the activities over that which would otherwise be attained through the coexistence of MnO and Co_2O_3 .

In view of the above, a range between 0.02 weight percent and 0.50 weight percent is selected for the effective range of Co_2O_3 content.

EXAMPLE 7

Results shown in Table 7

Table 7 shows the results obtained for a mixture of the basic composition of the same constituents as in Example 6 and an additional constituent of 0.10 weight percent of cobalt sesquioxide (Co_2O_3) alone and also for various mixtures with additions of manganous oxide (MnO) of from 0.02 weight percent to 0.50 weight percent as noted in Table 7.

TABLE 7

6	$Pb(Zr_{0.52}Ti_{0.48})O_3$ plus 0.20 wt. percent MnO plus 0.20 wt. percent Co_2O_3	67	410
7	$Pb(Zr_{0.52}Ti_{0.48})O_3$ plus 0.20 wt. percent MnO plus 0.30 wt. percent Co_2O_3	64	370
8	$Pb(Zr_{0.52}Ti_{0.48})O_3$ plus 0.20 wt. percent MnO plus 0.50 wt. percent Co_2O_3	57	350

¹ Cobalt carbonate ($CoCO_3$) is added as calculated on the basis of Co_2O_3 .

The results Nos. 1 and 2 of Table 6 show that the addition of 0.20 weight percent of MnO alone to the basic composition provides a piezoelectric material of a fairly elevated Kr factor. The increase in the value of Kr and Qm due to the addition of MnO provides piezoelectric materials having a wider field of application and they serve as improved piezoelectric materials. A comparison of the results Nos. 1 and 2 of Table 6 with the results Nos. 3 through 8 of this table proves that addition of both MnO and Co_2O_3 from 0.02 weight percent to 0.50 weight percent of Co_2O_3 to the basic composition remarkably raises both of the factors Kr and Qm.

As already observed, an increase in one of the factors Kr and Qm results in decrease in the other. However, the addition of both MnO and Co_2O_3 to the basic composition as the additional constituents remarkably increases both Kr and Qm factors, thereby providing piezoelectric materials having raised Kr and Qm factors. Such materials are excellent for use in ceramic wave filters where large Kr factors are required and in transducers for mechanical filters.

55 percent of Co_2O_3 alone to the basic composition yields a piezoelectric material having fairly augmented Kr and Qm factors. Further increases in the Kr and Qm factors to a large extent, which were augmented by the addition of Co_2O_3 to the basic composition, would provide piezoelectric materials having a wider field of application. Such further increases are accomplished, as shown in Table 7, by addition of both MnO and Co_2O_3 .

Referring to FIG. 4 of the drawing, the piezoelectric properties Kr and Qm are plotted versus the content of MnO for the results of Table 7 and the result No. 5 of Table 6. This figure clearly shows that when the content of MnO falls between 0.02 weight percent and 0.50 weight percent, excellent piezoelectric materials are obtainable.

When the content of MnO is less than 0.02 weight percent, the coexistence of MnO and Co_2O_3 contributes but little to the improvement of the piezoelectric activities otherwise attained by the presence of Co_2O_3 alone and responds little to improving the activities by the concurrent addition of MnO and Co_2O_3 . When the content of MnO exceeds 0.50 weight percent, the properties are so

rigidly altered regardless of the presence of MnO that the coexistence of Co_2O_3 hardly improves the properties.

such composition 0.10 weight percent of MnO and 0.10 weight percent of Co_2O_3 .

TABLE 8

No.	Composition	Kr, percent	Qm
15	$\text{Pb}(\text{Zr}_{0.50}\text{Ti}_{0.50})\text{O}_3$	29	340
16	$\text{Pb}(\text{Zr}_{0.50}\text{Ti}_{0.50})\text{O}_3$ plus 0.10 wt. percent MnO plus 0.10 wt. percent Co_2O_3	58	610
17	$\text{Pb}(\text{Zr}_{0.53}\text{Ti}_{0.47})\text{O}_3$	41	300
18	$\text{Pb}(\text{Zr}_{0.53}\text{Ti}_{0.47})\text{O}_3$ plus 0.10 wt. percent MnO plus 0.10 wt. percent Co_2O_3	66	490
19	$\text{Pb}(\text{Zr}_{0.55}\text{Ti}_{0.45})\text{O}_3$	39	320
20	$\text{Pb}(\text{Zr}_{0.55}\text{Ti}_{0.45})\text{O}_3$ plus 0.10 wt. percent MnO plus 0.10 wt. percent Co_2O_3	62	590

In view of the above, a range between 0.02 weight percent and 0.50 weight percent is selected for the effective range of the MnO content.

As already suggested hereinabove, the improvements made in piezoelectric properties by the addition of both MnO and Co_2O_3 clearly result from the presence of man- 15 ganous and cobalt ions. Various ways may be employed to introduce managanous and cobalt ions into the compositions. As exemplified in Tables 6 and 7, the oxides themselves may be added, or, if desired, managanous or manganese and cobalt compounds may be employed provided they are decomposed into the respective oxides at elevated temperatures. It is thus possible to introduce managanous ions into the compositions by using, in place of managanous oxide (MnO), managanous carbonate (MnCO_3) or any other managanous or manganese compositions, and, to introduce cobalt ions into the compositions, to utilize cobalt carbonate (CoCO_3) or any other cobalt compound

Table 8 clearly shows that change of x and y in the ceramic materials whose basic composition is given by the above-noted formulae does not degrade the piezo electric properties otherwise improved by coexistence of MnO and Co_2O_3 .

Compositions improved by the addition of both MnO and Co_2O_3 have excellent properties for use in manufacturing the elements of ceramic wave filters and the transducers of mechanical filters.

EXAMPLE 9

Results shown in Table 9

Table 9 shows the piezoelectric properties of ceramics given by the formula $\text{Pb}(\text{Zr}_x\text{Ti}_y\text{Sn}_z)\text{O}_3$ where $x=0.47$, $y=0.48$, and $z=0.05$ and where $x=0.42$, $y=0.48$, and $z=0.10$ and those obtained by adding to each of the compositions 0.10 weight percent of MnO and 0.10 weight percent of Co_2O_3 , as indicated in Table 9.

TABLE 9

No.	Composition	Kr, percent	Qm
21	$\text{Pb}(\text{Zr}_{0.47}\text{Ti}_{0.48}\text{Sn}_{0.05})\text{O}_3$	40	280
22	$\text{Pb}(\text{Zr}_{0.47}\text{Ti}_{0.48}\text{Sn}_{0.05})\text{O}_3$ plus 0.10 wt. percent MnO plus 0.10 wt. percent Cr_2O_3	62	470
23	$\text{Pb}(\text{Zr}_{0.42}\text{Ti}_{0.48}\text{Sn}_{0.10})\text{O}_3$	41	300
24	$\text{Pb}(\text{Zr}_{0.42}\text{Ti}_{0.48}\text{Sn}_{0.10})\text{O}_3$ plus 0.10 wt. percent MnO plus 0.10 wt. percent Co_2O_3	61	520

instead of cobalt sesquioxide (Co_2O_3). When managanous or manganese and cobalt compounds, other than MnO and Co_2O_3 are utilized, they should be used in their respective equivalent amounts to effect the desired weight of MnO and Co_2O_3 . Use of such compounds is exemplified by the compositions No. 6 in Table 6 and No. 13 in Table 7. In this connection, it should be understood that, according to this invention, managanous oxide (MnO) and cobalt sesquioxide (Co_2O_3) as used throughout this application, shall also mean and include such managanous or manganese and cobalt compounds which may be ther-

45 Comparison of the result No. 5 of Table 6 with Table 4 clearly shows that substitution of tin (Sn) for a portion of the basic composition does not appreciably degrade the piezoelectric properties otherwise improved by coexistence of MnO and Co_2O_3 without the tin substitution.

EXAMPLE 10

Results shown in Table 10

Table 10 shows the results obtained by substituting barium, strontium, and/or calcium for 5 atom percent of the lead in the composition No. 24 of Table 9.

TABLE 10

No.	Composition	Kr, percent	Qm
25	$(\text{Pb}_{0.9}\text{Ba}_{0.05})(\text{Zr}_{0.42}\text{Ti}_{0.48}\text{Sn}_{0.10})\text{O}_3$ plus 0.10 wt. percent MnO plus 0.10 wt. percent Co_2O_3	65	520
26	$(\text{Pb}_{0.9}\text{Sr}_{0.05})(\text{Zr}_{0.42}\text{Ti}_{0.48}\text{Sn}_{0.10})\text{O}_3$ plus 0.10 wt. percent MnO plus 0.10 wt. percent Co_2O_3	66	490
27	$(\text{Pb}_{0.9}\text{Ca}_{0.05})(\text{Zr}_{0.42}\text{Ti}_{0.48}\text{Sn}_{0.10})\text{O}_3$ plus 0.10 wt. percent MnO plus 0.10 wt. percent Co_2O_3	63	5,000

mally decomposed into managanous oxide (MnO) and cobalt sesquioxide (Co_2O_3), respectively.

EXAMPLE 8

Results shown in Table 8

Piezoelectric characteristics are shown in Table 8 for typical ceramics obtained by selecting 0.50-0.55 and 0.50-0.45 for x and y , respectively, while maintaining 0.00 for z in the formula $\text{Pb}(\text{Zr}_x\text{Ti}_y\text{Sn}_z)\text{O}_3$, by adding to

70 75 Table 10 clearly shows that the piezoelectric properties are substantially equally well improved by the coexistence of MnO and Co_2O_3 for both cases considered, where at least one member of the group of barium, strontium, and calcium is substituted for a portion of the basic composition and where no such substitution is effected.

Examples 9 and 10 show that, in accordance with this invention, an excellent piezoelectric material may be produced by the addition of both MnO and Co_2O_3 to the basic compositions consisting not only of lead titanate-

lead zirconate solid solution but also of lead titanate-lead zirconate-lead stannate solid solution. Still further, excellent piezoelectric materials may be produced with such solid solution compositions in which a portion of the lead in these solid solutions is replaced by at least one alkaline earth metal.

While this invention has been set forth in certain particular compositions merely for illustration, it will be understood that the general principles of this invention may be applied to other and widely varied compositions without departing from the spirit of the invention and the scope of the appended claims.

What is claimed is:

1. A piezoelectric ceramic composition having a basic composition represented by the following compositional formula

where A represents at least one member selected from a group consisting of calcium, strontium, and barium and u , v , x , y and z are given by

$$\begin{aligned} u &= 0.75-1.00, \\ v &= 0.00-0.25, \\ u+v &= 1.00, \\ x &= 0.00-0.90, \\ y &= 0.10-0.60, \\ z &= 0.00-0.65, \text{ and} \\ x+y+z &= 1.00, \end{aligned}$$

characterized in that said ceramic composition contains a set of additional constituents consisting of a chromium compound equivalent in amount to a chromium sesquioxide of from 0.01 to 0.30 weight percent and a cobalt compound equivalent in amount to a cobalt sesquioxide of from 0.02 to 0.50 weight percent, each of the weight

30
35

30
35 106-39

percentages being the percentage of the total weight of said ceramic composition.

5 2. A piezoelectric ceramic composition according to claim 1, wherein the set of said additional constituents consists of chromium sesquioxide of from 0.01 to 0.30 weight percentage and cobalt sesquioxide of from 0.02 to 0.50 weight percent, each of the weight percentage being the percentage of the total weight of said ceramic composition.

10 3. A piezoelectric ceramic composition having the following formula

where

$$\begin{aligned} x &= 0.00-0.90, \\ y &= 0.10-0.60, \\ z &= 0.00-0.65, \text{ and} \\ x+y+z &= 1.00, \end{aligned}$$

characterized in that said ceramic composition contains a set of additional constituents consisting of chromium sesquioxide of from 0.01 to 0.30 weight percent and cobalt sesquioxide of from 0.02 to 0.50 weight percent, each of the weight percentages being the percentage of the total weight of said ceramic composition.
